UNITED STATES PATENT OFFICE.

ARTHUR W. BROWNE, OF PRINCE'S BAY, NEW YORK, ASSIGNOR TO THE
S. S. WHITE DENTAL MANUFACTURING COMPANY, OF PHILADELPHIA,
PENNSYLVANIA.

DESIGN FOR A BOX FOR ELECTRIC MOTORS.

SPECIFICATION forming part of Design No. 25,028, dated December 31, 1895.

Application filed October 12, 1895. Serial No. 565,522. Term of patent 14 years.

To all whom it may concern:

Be it known that I, ARTHUR W. BROWNE, of Prince's Bay, in the county of Richmond and State of New York, have invented a new and original Design for a Box for Electric Motors, of which the following is a specification, reference being had to the accompanying drawings, in which—

Figure 1 is a top perspective view, and Fig. 2 a bottom perspective view, of the box; and Fig. 3 a plan view of the bottom part of the box detached from the top part.

The leading features of my design are the two-part box with its top part having two perforated projections or lugs, one near each corner of its front wall, and with its bottom part having a front flange slotted parallel with the front wall of the box and a rear flange slotted parallel with the rear wall of the box, and also having a hollow flange or inverted trough-like partition extending from the front wall of the box-bottom to its slotted rear flange.

A is the top part of the box having the perforated lugs *a a* near its opposite front corners. 25

B is the bottom part of the box provided with the outside front flange *C* with the slot *c* parallel with the front wall of the box, and having the outside rear flange *D* with the slot *d* parallel with the rear wall of the box. The bottom part is also provided with the hollow flange or inverted trough-like partition *F* extending rearwardly from the front of the bottom part to the slotted rear flange thereof. 30 35

I claim as my invention—

The design for a box, substantially as shown and described.

In testimony whereof I affix my signature in presence of two witnesses.

ARTHUR W. BROWNE.

Witnesses:

SEYMOUR CASE,
M. A. COLE.
